(57) **CLAIM**

The ornamental design for an electrical therapy device as shown and described.

DESCRIPTION

The patent or application file contains at least one drawing executed in color. Copies of this patent or patent application publication with color drawing(s) will be provided by the Office upon request and payment of the necessary fee.

1. Electrical therapy device

1.1 : Perspective

1.2 : Front

1.3 : Back

1.4 : Left

1.5 : Right

1.6 : Top

1.7 : Bottom

Figure 1.1 is a perspective view of an electrical therapy device, showing my new design.

Figure 1.2 is a front view thereof.

Figure 1.3 is a back view thereof.

Figure 1.4 is a left view thereof.

Figure 1.5 is a right view thereof.

Figure 1.6 is a top view thereof.

Figure 1.7 is a bottom view thereof.

The part covered by red color in Figure 1.1 to Figure 1.7 forms no part of the claimed design.

The part not covered by red color form the part of the claimed design.

1 Claim, 7 Drawing Sheets
(6 of 7 Drawing Sheet(s) Filed in Color)
